A. A. JOHNSON

TYPEWRITING MACHINE

Filed Sept. 11, 1920

INVENTOR: A. A. JOHNSON

Arthur A. Johnson

UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed September 11, 1920. Serial No. 409,625.

To all whom it may concern:

Be it known that I, ARTHUR A. JOHNSON, a citizen of the United States, resident of the city of New York, county of the Bronx, and State of New York, have invented new and useful Improvements in Typewriting Machines, of which the following is a specification.

This invention relates to typewriting machines and particularly to typewriting machines of the "fan-fold" type.

In this type of machine, a reciprocatory carbon carriage is provided with means for holding the carbon sheets in position between the folds of a fan-fold sheet, so that, after a form has been written and the platen shifted to straighten the webs, the carbon sheets may be moved into proper superposed relation to a fresh "form". The means here-
20 tofore employed for holding carbon sheets is only adapted for use with a fan-fold web or separate superposed webs.

A feature of this invention is the provision of means for enabling the use of a folded web having one or more of its free edges turned in, so that part or parts of the web comprise two sheets or plies folded on each other with the open part of the sheets adjacent a fold of that part of the web and
30 another part.

The means for doing this may comprise an arm made up of two parts, welded or otherwise connected for part of its length and having one free part bent up at the
35 end of the secured part and another free part bent down at the end of the secured part. These bent-up and bent-down portions are then bent around to extend parallel to the secured parts of the arms. Each
40 part of the arm is provided with means for holding the carbon to the arm.

The advantage of using a closed fold sheet will be manifest when it is considered that with this form of sheet there will be
45 no free edges at the top and bottom of the pack to catch on to parts of the machine or to fall over after the form has been written upon.

Other features and advantages will be
50 manifest to those skilled in the art.

In the accompanying drawings:

Fig. 1 is a perspective view showing a carbon arm of the present invention;

Fig. 2 is a perspective view of one form of folded web which may be used according to the present invention; 55

Fig. 3 shows a carbon arm for the form of web shown in Fig. 2;

Fig. 4 shows another form of web which is part fan-fold and part closed-fold which 60 may be used according to the present invention;

Fig. 5 shows the arrangement and form of carbon arms used with the form of web shown in Fig. 4. 65

In the fan-fold type of typewriting machine, the carbon shifting mechanism comprises a reciprocatory carriage mounted on suitable guide rails and having a handle by means of which it is operated. This 70 carriage is provided at its side edges with blocks or standards forming supports for carbon carrying arms. Each of these carbon arms is usually a flat bar which is connected to one of the standards and extends 75 inwardly between the folds of the fan-fold sheet. The carbon sheet is secured to a carbon arm by a sheath or clamp embracing the arm and pivoted thereto. The carbon arm can only be used with a web in 80 which the part to receive the carbon impression has an open edge so that the carbon arm can extend directly from the supporting block or standard into the web. This condition exists in the ordinary fan-fold web. 85

To enable the use of folded webs having parts thereof closed by other parts so that there is no free edge to the web at the portion thereof to receive the carbon impression, I provide a carbon arm which extends into the web through an open fold to the opposite side of the web where it bends around the free edge of the web and extends into the closed fold. 95

Referring now to the web 16, shown in Figs. 4 and 5. This web 16 is somewhat similar to a fan-fold web in that it has parts 17, 18, 19 and 20 folded upon each other, zigzag fashion, but differing therefrom, in that the part 21, instead of being folded over the part 20, is folded under, between part 20 and part 19, and in that part 22 is folded over the part 17, between part 18 and part 17, instead of under part 17. 100 The part 22 has its free edge 23 adjacent the 105

fold of the parts 17 and 18 and the part 20 has its free edge 24 adjacent the fold of the parts 19 and 20. The carbon arm 25 of the present invention comprises a bar 26 secured to the standard 15 in the usual manner and extending into the web 16 between the parts 21 and 19, and carries a carbon sheet 21^c for the part 21. To provide means for carrying the carbon sheet 20^c for the part 20, the bar 26 has an extension 27 bent at 24^b around the free edge 24 of the part 21 and lying substantially parallel to the bar 26. The arm 25 is provided with a carbon clamp 28 pivoted at 29 to the extension 27 and another clamp 29^a pivoted to the bar 26 at 30. The carbon arm 31 of the present invention is substantially the same as the arm 25 and comprises a bar 32 secured to the standard 15 in the usual manner and extending into the web 16, between the parts 18 and 22, and carries a carbon sheet 18^c for the part 18. The bar 32 has an extension 33 bent at 23^b around the free edge 23 of the part 22 and lies substantially parallel to the bar 32. The arm 31 is provided with a clamp 34 pivoted at 35 on the extension 33 and a clamp 36 pivoted at 37.

To provide a carbon arm for the part 19 an ordinary arm 13 is provided.

Referring now to Figs. 2 and 3. These views show a web 38, which is somewhat similar to the web shown in Fig. 4 and Fig. 5, except that there are no parts corresponding to the parts 18 and 19 of Figs. 4 and 5. This web comprises a part 39, folded on a part 40, and a part 41, folded on a part 42; and one-half 39—40 over on the other half 41—42, thus forming a four part web having an opening 43. To provide means for carrying the carbon sheet 41^c, the carbon arm 44 comprises a bar 45 having a suitable clamp 46 for holding the carbon sheet 41^c thereto. The arm 44 extends into the opening 43 of the web 38. As shown more clearly in Fig. 1, the bar 45 comprises two sections or extensions 47 and 48 in the form of bars, said extension 47 being bent at 49 about the free edge 50 of the part 41 and extending parallel to the bar 45, and said extension 48 being bent at 51 downwardly and around the free edge 52 of the part 39 and extending parallel to the bar 45. The extension 47 carries a carbon sheet 42^c for the part 42, while the extension 48 carries the carbon sheet 39^c for the part 39. Preferably, the carbon arm 44 is made of two strips or bars of material welded or otherwise secured together for part of their length and having their unsecured parts, one bent up and around and the other part bent down and around to form the extensions 47 and 48, although other forms may be used. The extensions 47 and 48 each carry clamps 53 for holding the carbon sheets thereto.

From the foregoing, it will be seen that I have provided means whereby the carbon sheets may be carried in proper superposed relation to the parts of a folded web having one or more closed folds.

It will be understood that the term closed fold is intended to mean a fold in the web the nature of which is such that one or more of the parts of the folded web cannot be reached without entering an opened fold in the web and then passing around the free edge of the web.

Variations may be resorted to within the scope of my invention and portions thereof may be used without others.

Having thus described my invention, I claim:

1. A carbon-holder for manifolding typewriting machines, comprising a bar supported at one end to extend therefrom into an open fold of a web, and a carbon-holding arm supported on the free end of the bar and extending parallel to the bar and toward the supported end thereof to enter a closed fold of the web formed by folding the portion of the web on one side of the first-mentioned fold into the latter.

2. In a typewriting machine of the fan-fold type, means for holding a carbon sheet in superposed relation to a part of a folded web and to extend into an open fold of said web, and means for holding a carbon sheet in superposed relation to another part of the folded web to extend into a closed fold in said web.

3. In a typewriting machine of the fan-fold type, means for holding a carbon sheet in superposed relation to a part of a folded web and to extend into an open fold in said web, and means for holding a carbon sheet in superposed relation to another part of the folded web to extend into a closed fold in said web; said second means being formed integral with the first means and extending substantially parallel to the first means and in spaced relation therewith.

4. In a typewriting machine of the fan-fold type, means for holding a carbon sheet in superposed relation to a part of a folded web and to extend into an open fold in said web, means for holding a carbon sheet in superposed relation to another part of said web to extend into a closed fold in said web, said second means being formed integral with the first means and extending substantially parallel to the first means and in spaced relation therewith, and carbon clamping members carried by all of said carbon carrying means.

5. A carbon-holder, for use in a typewriting machine of the fan-fold type, comprising a carbon-holding bar to enter a central fold of a continuous web, and carbon-holding arms supported on the end of the bar adjacent the crease of the fold, and extend-

ing parallel to the bar and spaced therefrom to enter closed folds formed by folding the free edges of the plies forming the first-mentioned fold into the same.

- 5 6. A carbon-holder, for use in a typewriting machine of the fan-fold type with a continuous web having a longitudinal central fold and additional folds formed by folding the side portions of the web into
10 the central fold, comprising a portion for each of the additional folds to hold the carbon-sheet therein and a portion to hold a carbon-sheet in the central fold and between

the parts of the web folded into the central fold to form the additional folds.

7. A carbon arm comprising a pair of bars secured together for part of their length, one of said bars being bent upwardly and the other bar being bent downwardly at their unsecured portions, both of said bent bars being further bent to lie substantially parallel to and spaced from said secured portions of said bars.

In testimony whereof, I have signed my name to this specification.

ARTHUR A. JOHNSON.
